UNITED STATES PATENT OFFICE.

ROBERT P. GARSED, OF NORRISTOWN, PENNSYLVANIA.

ANNUNCIATOR.

SPECIFICATION forming part of Letters Patent No. 430,735, dated June 24, 1890.

Application filed June 19, 1889. Serial No. 314,884. (No model.)

To all whom it may concern:

Be it known that I, ROBERT P. GARSED, a citizen of the United States, residing at Norristown, in the county of Montgomery and State of Pennsylvania, have invented a new and useful Improvement in Annunciators, of which the following is a specification, reference being had to the accompanying drawings to more clearly set forth the device.

10 The object of my invention is to produce a compact, easily made and adjusted, and a cheap and durable annunciator, whose simplicity of construction and operation and easy of repair makes it at once desirable. 15 Besides being novel in many of its parts, it relates as well to improvements on my patents, Nos. 384,144 and 389,378. These objects are accomplished by, and my invention consists in, certain novel features of construction and in combinations of parts, more fully described hereinafter, and particularly pointed out in the claims.

Figure 1 is a perspective of the annunciator, showing air-tubes therefor and one 25 of the number or indicator plates dropped. Fig. 2 is a side elevation with the sides of the casing removed to show the operating mechanisms. Figs. 3, 4, and 5 are respectively top, bottom, and rear views of the annunciator-case. Fig. 6 is a cross-section on the line 30 *x x*, Fig. 2. Fig. 7 is a front view of the main air-chamber, with the valves and depending expansible bodies removed and the lower portion of the chamber removed, showing one 35 of the restoring-levers and its operating-rod. Fig. 8 is a similar side or edge view. Fig. 9 is a rear elevation of the main air-chamber, showing two valves and chambers, the restoring-levers being removed. Fig. 10 is a 40 detail section of one of the valves and its depending expansible bodies. Figs. 11 and 12 are detail views.

A represents the hinged sides of the annunciator-case with glass A', of shape as 45 shown, set in the forward parts of said sides.

B represents the number-board of the device, having a foot B', with a groove D for the reception and support of the glass front C.

E is the top of the case having a groove E' 50 for reception of the glass C, and an opening E'' for the end of the main air-chamber F to pass through in making connection with bell

G, which bell or gong is rung by the influx of air to bellows G', which, rising, causes an attached metal rod G⁵, having a flexible band 55 at its upper end, to rise with it, and the band being wound around a shaft carrying a toothed wheel, with pallets (and a hammer-rod with head G⁴ attached in turn to them) gearing with said wheel. The bell is struck 60 by the revolving of the shaft and wheel and the consequent vibration of the hammer-head, as will be understood from such a well-known construction.

G'' are the brackets holding the alarm-operating mechanism to support the bell, and G''' is the wooden box covering such mechanism. The bell-supporting board in turn is fastened to the front of the top part of the back board of the annunciator-case. It will 70 be seen that any bell-sounding mechanism can be applied to the device.

F' are inlets to the main air-chamber, on which the valves H are screwed. These valves have a back inlet H', a side outlet H'', and a 75 bottom outlet H''', and are coupled to the air-pipes W at their back inlets.

F'' are journal-bearings integral with the main air-chamber, and the restoring-arm pivots I' pass through them. I are such restoring-arms. They have a vertical pivotal motion in restoring the number-plates J to their 80 first position. They are bifurcated both front and back of their cross-piece.

K are the number-plate levers. They have 85 a shoulder K' at their head end to hold plate J in place, and are pivoted by brackets L, through which they pass, to the rear of the number-board B of the device. These brackets L are made in one piece with ribs L', having 90 opposite holes for the passage of pivots L''. They also at their lower part have a projection and a hole for a screw to hold the flat spring M in place, which spring returns the lever K to position after said lever is pressed 95 upon by the bellows N in the operation of the device. These bellows are flexible, and either expand or collapse as the air enters or escapes from them, and at their upper part are held to valve H by a flanged connecting-piece with 100 thread, as shown, the hole N'' for passage of air through the flange being very small, for purposes as will be referred to. The flanged connecting-piece N''' at the bottom of bel-

lows, after being inserted through a hole in this part of bellows, (the upper connecting-piece being likewise inserted,) has an outside washer O and a threaded socket O', which 5 when screwed on the projecting piece of this connecting-piece bears upon washer O and makes said bellows at this part air-tight, as well as guiding it in its bearing upon lever K, and its length being only equal to the 10 thickness of the bifurcated end of said lever, compactness is here gained in the construction of the device.

P are brackets on the main air-chamber, by which it is held to the number-plate board B. 15 These brackets have a space between them, in which the restoring-rod q works either up or down. This restoring-rod, being attached by pins to the restoring-arms I through the slot, as shown in Figs. 2 and 7, when moved 20 upwardly returns the hinged number-plates to their first position after they have dropped to show the point from whence the device has been operated, the turned-up points of these restoring-arms being suited to bear against 25 the rear of said number-plates.

R are the case or gaging brackets for the four inside corners of the annunciator, and are so made that the top E and the bottom T of the device are held to the back frame 30 S, from which it is never necessary to separate them, and the horizontal arms of these brackets with turned ends gage the distance to place the number-board B, beneath the top E, to allow space for the number-plates to 35 rise and fall. They also give a better bearing to said number-board at its extremities.

U is the top bracket, and V is the bottom bracket of the case to hold it in position on a wall or other suitable place. They are made 40 each of one piece, the top one having a uniting cross-bar and upturned ends to receive wall-screws, the bottom bracket being made, as shown in Fig. 4, with downwardly-turned ends next the wall. It will support the case 45 in position on said wall, hold the sides A in place, when their screws may be removed in the adjustment of the apparatus, and hold the board B in place by supporting its foot B', whether the sides A be off or on. The 50 downwardly-turned bifurcated ends, resting on screws, serve the first purpose. The laterally-projecting parts V' serve the second purpose, while the horizontally-projecting parts V'' support the number-board B in place 55 whether the sides A be off or on. The glass C, Fig. 2, it will be seen, may be put in or taken out edgewise from either side of the annunciator, when a forward part of the sides A are removed, as the grooves E' and D are 60 open at their ends. They are unseen when said sides are on.

The back S of the annunciator-case is made with an offset s' and narrower at its upper part, not only in size to suit the bell apparatus to be fastened to it, but to allow the upturned parts U' of the top bracket room for fastening to a wall without taking up more

room than the line of the sides A of the devices. There are openings S'' in the back S, through which the ends of the pipes or conductors W pass to connect with the valves H within the case, and also within a suitable distance of the edge of this back (see Fig. 3) it is fluted to suit the thickness of the conductors W and allow them to pass without projecting beyond the line of the rear face of said back. This allows free adjustment of and non-pressure to the pipes or conductors when the case is in place. With the pipes in or out of position parts of the device may 70 be removed, when necessary, without taking the back with its attached bottom and top from their place upon a wall. This feature of the device is highly advantageous. The flute of the back extends to the lower edge of 75 bottom opening S'', as indicated by dotted lines x x, Fig. 5.

The operation of the device is as follows: Air being forced through a pipe W in any of the well-known ways from a certain room, 80 story, &c., it enters the valve H through its back inlet H', attached to that pipe, and going into bellows N inflates the same and depresses the inner end of lever K, causing its outer end to rise, with the effect that its number-plate J falls from its upright position (in 85 this case No. 3, Fig. 1) and indicates the place of operation. During this operation the air has also raised the plunger of the valve H and passed through outlet H'' into the main 90 air-chamber F, which to a desired distance is hollow, as indicated by dotted lines in Figs. 6 and 7, and by its connection with the bell mechanism (see Fig. 2) raises bellows G', which in any of the well-known ways may 95 sound an alarm. Simultaneously with this action the plunger of the valve H has fallen unsteadily, although by gravity, to its first position. The plunger, thus prevented from regaining its seat quickly, allows some escape of air within the chamber, and it almost regains its normal condition by the 100 time the device has been operated, and so becomes self-regulating in such operation, it being understood that were these plungers quick 105 to regain their seats and there were no escape for the air within the main air-chamber the bellows G would be continuously distended and the device would not be operative to 110 its full extent.

In the operation of the device it will be understood that the plungers of the valves not operated by air from their pipes W are supposed to remain upon their seats, that the air in the main chamber may not by entering through 115 the outlets H'' of these valves cause their bellows to distend and their number-plates to drop, which is not wanted. The escapement of air by a return course through the plungers of the valves not operated by air from 120 their pipes in a small measure does, however, take place, because of the air being in motion and jumping, as before stated, within the main chamber, which draws these plungers from 125 130

their seats, and to obviate the entrance in this way of enough air to their bellows to cause their numbers to drop, the small holes N'', instead of large ones, are made through the flanges before referred to, as the air will better escape to the larger openings in the back outlets H' to the pipes. The flat spring M, held in place as shown, presses at its upper end upon the under side of the inner end of number-lever K and keeps it engaged with the number-plate J, allowing also by its elasticity of the movement of said lever when operated. When any or all the number-plates are down, they may be restored to position by pushing upward the projecting end of the restoring-rod q, Fig. 2, after which said rod, by gravity with its attached restoring-arms, returns to its first position. When the sides A are in place, it will be seen that the grooves that hold the plate C in place are covered; also, that said sides may be opened either way upon their hinges when necessary to get at any part of the apparatus.

Having thus described my invention, what I claim as new, and desire to secure by Letters Patent, is—

1. In an annunciator, the combination of the vertical back board or frame having one or more transverse openings for the passage of the tubes and being reduced or fluted upwardly and centrally from the said apertures to receive said tubes, the top and bottom boards secured to said back board, the securing-brackets secured, respectively, to said top and bottom, the number-board parallel with said back and secured to the top and bottom, a glass front inclosing sides, and the operating mechanism for the number-plates.
2. In an annunciator, the combination of the back having a transverse opening and longitudinally fluted on its rear face upwardly from said opening, horizontal top and bottom boards secured to said back, the number-board between said top and bottom, the inclosing sides and front, the number-plates and operating mechanism therefor, said back having a reduced upward extension, and the bell and operating mechanism carried thereby, substantially as described.
3. In an annunciator, the combination of the back frame, the forwardly-extending horizontal top secured thereto, the parallel bottom board secured to the lower end of said back, the vertical number-board in a distance in front of the back and secured to the said top and bottom and having a forwardly-extending foot at its lower end, the front glass movable between the top and said foot, the sides having hinged doors behind the number-board, and the box above and carried by said top to inclose the audible alarm.
4. In an annunciator, the combination, with the back, top, bottom, and number boards of the case, of the internal braces respectively securing the back, top, and number board and the back, bottom, and number board together, the exterior supporting and securing

brackets on said top, and the single integral supporting and securing bracket on the bottom of the case, substantially as described. 70

5. In an annunciator, the combination, with the indicating and operating mechanisms, of the case inclosing the same, consisting of the back, a number-board, the top covering the same, means for securing the case carried by said top, a bottom board secured to the lower ends of said number-board and back, the sides of the case, and the integral bracket secured to said bottom having arms projecting beneath the number-board and sides and with bent inner ends to engage supporting means. 75

6. In an annunciator, the combination, with a slotted or perforated number-board and the series of number-plates hinged to the front side thereof, of means to normally hold said plates raised, a main air-chamber secured to the rear side of said board, inflatable bodies carried by said chamber to separately operate said means to exhibit the number-plate desired, and the air-tubes, substantially as described. 80

7. In an annunciator, the combination, with a number-board and number-plates hinged thereto, of means normally holding said plates in readiness to exhibit the same separately, 95 and a main air-chamber secured to said board and provided with lateral tubes or valves and inflatable bodies carried by said valves, each arranged when inflated to operate said means to drop a number-plate, and the air-tubes, 100 substantially as described.

8. In combination, a support, the swinging number-plates, each plate being provided with means for normally holding it raised, an inflatable body for each plate provided with an air-tube and arranged to operate said means to drop the plate when inflated, an air-chamber into which said bodies discharge, an audible alarm-operating mechanism, and an inflatable body, into which said chamber discharges, adapted to operate said mechanism, 110 all arranged substantially as described.

9. The combination of the number-board, the normally-raised swinging number-plates hinged to the front thereof, an air-tube for each plate, each connected to throw down its plate when an impulse of air passes through the same, the main air-chamber secured to the rear of said board and with which said tubes are connected, and the alarm operated 115 by the air in said chamber, substantially as described.

10. The combination of the number-board, the swinging number-plates on the front side thereof arranged in vertical series, means to 125 separately throw down and display said plates, the vertically-swinging restoring-levers for said plates pivoted at their inner ends to a suitable support in rear of said board with their free ends extending through the board beneath the plates, and the vertical operating-rod joined to said levers by a slot and pin to swing them vertically, as set forth. 130

11. In an annunciator, the combination of

- a support, the vertically-swinging normally-raised number-plates, an air-chamber, an audible alarm operated by the air in said chamber, an air-tube for and to operate each number-plate, and a valve for each tube having a reduced opening through which the air to operate the number-plate passes, and a larger valved opening into said chamber, arranged and operating substantially as described.
12. In an annunciator, the combination of the number-board, the swinging number-plates hinged to the front side thereof, a holding and releasing lever for each plate pivoted to and extending through the board, and each provided with a spring for yieldingly holding it in position, an inflatable body for each lever, an air-tube for each body, and a main air-chamber into which said bodies discharge.
13. The combination, with the name-board and index or name plates hinged thereto, of the main air-chamber, the audible alarm mechanism, an expandible hollow body connected with said chamber and operating the audible alarm mechanism, releasing mechanism for each plate, the separate expandible bodies carried by and connected with said chamber for each number-plate, and the tubes connected with said last-mentioned bodies.
14. The combination of the number-board, the swinging plates carried thereby, the main vertical air-chamber secured to the rear side of said board, the expandible flexible body

into which the upper end of said chamber discharges and connected with and adapted to operate the audible alarm, and the series of hollow expandible bodies to operate said plates connected with the air-tubes and separately discharging into said chamber.

15. In an annunciator, the combination of the main air-chamber having securing and supporting feet, and lateral journal-lugs, the number-board to which said feet are secured, the number-plates, restoring-levers for said plates extending through the board and journaled on said lugs, the holding-levers for said plates, the valves secured to and opening into said chamber and carrying hollow expandible bodies bearing on said holding-levers, and the tubes opening into said valves.

16. In an annunciator, the combination, with the main air-chamber and audible alarm mechanism operated by the air therefrom, of the lateral valves carried by said chamber and opening into the same, each containing a reciprocating valve and carrying a hollow expandible body into which the valve opens, the reduced inlet from said valve into said body, and the side opening into said valve for the air-tube, a swinging number-plate, and a holding-lever therefor operated by said expandible body.
